UNITED STATES PATENT OFFICE.

GEORGE W. ELSEY, OF ANDERSON, INDIANA, ASSIGNOR, BY MESNE ASSIGNMENTS, TO
DELCO-REMY CORPORATION, OF DAYTON, OHIO, A CORPORATION OF DELAWARE.

ENGINE-STARTING APPARATUS.

Application filed September 25, 1924. Serial No. 739,954.

This invention relates to starting apparatus for internal combustion engines and particularly to the type of apparatus which includes a pinion normally disconnected from the engine gear, an electric motor for driving the pinion and means for moving the pinion into engagement with the engine gear and for closing the motor switch. The pinion is threadedly connected with a 5 spirally-splined shaft driven by the motor, and means are provided for automatically disconnecting the pedal or other control device from the pinion so that the pinion will be automatically demeshed from the engine 10 gear when the engine becomes self-operative. In starters of this type the pinion is not always fully in mesh with the engine gear when the electric motor starts, consequently the pinion is quickly threaded into 15 complete driving engagement with the engine by operation of the motor. This rapid movement of the pinion is arrested suddenly by the pinion striking against the stop, thereby producing a noise which might be 20 considered objectionable by some automobile drivers.

It is one of the objects of the present invention to cushion the endwise movement of the pinion in order to reduce the amount of 25 noise attendant upon the engine-starting operation.

In starting devices employing a spirally-splined or screw-threaded driving connection between the motor and pinion there is 30 a tendency for the pinion to become partly demeshed from the engine gear during the cranking operation. This is due to variations in torque required for cranking the engine. The present invention aims to 35 overcome this difficulty by providing means which not only cushions the endwise movement of the pinion into engagement with the engine gear, but also tends to prevent partial demeshment of the pinion during the 40 cranking operation.

Further objects and advantages of the present invention will be apparent from the following description, reference being had to the accompanying drawings, wherein preferred forms of the present invention are 45 clearly shown.

In the drawings:

Figs. 1 and 2 are fragmentary side views of a form of starting apparatus embody-

ing the present invention, these views showing the apparatus in two positions of operation.

Figs. 3, 4 and 5 are fragmentary sectional views taken respectively on the lines 3-3, 4-4 and 5-5 of Fig. 1.

In the drawings, 20 designates the field frame of an electric motor which includes an armature 21 mounted on a shaft 22 having a spirally-splined portion 23 and a journal portion 24. The journal 24 is supported by a bearing 25 carried by the gear housing 26 to which the field frame 20 is attached. The spiral splines 23 are threadedly engaged by a motor pinion 27 adapted to move into engagement with and to drive a gear 28 provided by the flywheel of the engine.

A pinion-shifting apparatus which is permanently connected with the pinion includes a bifurcated lever 30 mounted on a rod 31 which is supported by the gear housing 26. Lever 30 engages the flanges 32 and 33 of a sleeve 34, to which is connected a cup-shaped member 35 secured to a second cup-shaped member 36 which includes a flange 37 which is notched to receive the teeth of the pinion 27. The hub of pinion 27 is provided with a threaded portion 38 of less diameter than the internal diameter of the notched flange 37. A nut 39 engages the portion 38 and provides a stop abutting the notched flange 37, thereby limiting the separation of the pinion 27 from the sleeve 34. A spring 40 interposed between the member 35 and the nut 39 tends to maintain the nut 39 in engagement with the flange 37. The pinion 27 is maintained normally out of contact with the gear 28 by spring 41, having one end 42 resting upon the frame 20, an intermediate portion encircling the rod 31 and an end 43 engaging the yoke 44 of the lever 30.

The motor frame 20 supports a starting switch 50 including an actuating plunger 51 normally maintained in contact-open position by spring 52. Means for closing the switch and for actuating the pinion-shifting lever 30, includes a pedal 53 connected by rod 54 with a lever 55 pivotally supported by the rod 31. Pedal 53 is normally maintained in the position shown in Fig. 1 by spring 56 interposed between the pedal 53 and a cup-shaped member 57 attached to the

floor-board 58 of an automobile, and provided with an opening through which the rod 54 extends. Means for connecting the lever 55 with the lever 30 includes a rod 60 which bridges the bifurcations 55^a of lever 55, and which pivotally supports a bifurcated latch having a yoke 61 and latch arms 62 each adapted to be received by a notch 63 provided in each of the arms of the lever 30. A coiled spring 64 which bears at one end against the yoke 61 and at the other end against a stud 65, serves normally to hold the latch arms 62 in engagement with the arms of the lever 30.

Means for disconnecting the pedal from the pinion-shifting lever 30 includes a bracket 70 attached by screws 71 to the motor frame 20 (see Fig. 4). Bracket 70 supports a pin 72 which pivotally supports ears 73 of a latch throw-out plate 74. Plate 74 is located in the path of movement of the latch yoke 61 and is urged toward yoke 61 by a coiled spring 75 surrounding the pin 72, bearing at one end against a stationary part and at the other end against the throw-out plate 74, as indicated at 76.

Means for cushioning the endwise movement of the pinion 27 into engagement with the engine gear 28, and for tending to prevent demeshment of the pinion 27 until after the engine becomes self-operative, includes a pneumatic cushioning device consisting of a cylinder member or portion 80 provided by the pinion 27, and a piston or plunger portion 81 which is attached to the shaft 24 in any suitable manner, such as by a screw-thread-and-pin connection, shown in the drawings. The housing 26 provides a plane bearing surface 82 which receives the thrust of the shaft 24 transmitted to it through the flanges 83 of the plunger member 81.

The operation of the invention is as follows: To start the engine the pedal 53 is pressed and motion is transmitted to the pinion 27 through rod 54, lever 55, latch arms 62, lever 30, flange 32 of sleeve 34, spring 40 and nut 39. In case the teeth of the pinion do not collide with the end faces of the flywheel gear teeth, the pinion 27 will be moved into partial engagement with the gear 28 and then the motor switch 50 will be closed by engagement with the plunger 51 of a screw 59 which is adjustably secured to the lever 55. The operation of the motor will cause the pinion 27 to be moved endwise into complete engagement with the engine gear 28, and motion of the pinion will be arrested by its engagement with the flange 83. During the movement of the lever 55 from the position shown in Fig. 1 to that shown in Fig. 2, the latch yoke 61 will strike the throw-out plate 74. As long as pressure is being transmitted from the pedal 53 to the lever 30 through the latch arms 62, the latch arms will not be disconnected from

the lever 30 although the springs 75 may be twisted more than initially, as shown in Fig. 1, by reason of engagement of the latch yoke 61 with the plate 74. This is due to the fact that the engaging surfaces of the lever arms 30 and the latch arms 62 are so disposed that the pressure between these surfaces prevents disengagement of the latch from the lever 30 until after this pressure is relieved. When the motor switch is closed so that the motor causes the pinion 27 to move axially independently of the pedal 53, pressure at the engaging surfaces of the latch arms 62 and the lever arms 30 will be relieved so that the spring-actuated throw-out plate 74 will be released to cause the latch to move into the position shown in Fig. 2. Therefore, when the engine starts the pinion will be automatically demeshed from the engine gear although the pedal 53 may still be held down to maintain the lever 55 in the position shown in Fig. 2.

In case the teeth of the pinion collide with the end faces of the flywheel gear teeth as the pinion is moved into engagement with the gear, the spring 40 will be compressed beyond its initial state of compression to permit the pedal 53 to close the motor switch 50. The motor will then rotate the pinion into registration for meshing with the gear 28 and the spring 40 will be released and will move the pinion 27 quickly into mesh with the gear 28.

The pinion recess or cylinder 80 is chamfered at 80^a, and the plunger 81 is chamfered at 81^a to facilitate the telescopic engagement of members 80 and 81 during the endwise movement of the pinion into engagement with the gear. During this engagement the air trapped in the cylinder 80 will be compressed suddenly, thereby tending to cushion and retard the movement of pinion 27 to the right in Fig. 1. This compression space, however, is vented to atmosphere through the crevices between the internal splines of the pinion 27 and the external splines 23 of the shaft 22. During cranking of the engine the pinion 27 abuts the stop flange 83. Therefore, there is no cranking through the cushioning device. In engine starters of this type which use a spring cushioning stop member, which encircles the pinion shaft and is located between the pinion and a member fixed to the shaft, the spring tends to move the pinion out of engagement with the engine gear during the cranking operation when the torque necessary to rotate the engine crank-shaft diminishes. The cushioning dash pot of the present invention tends to prevent demeshment of the pinion under these conditions because withdrawal of the cylinder 80 from the plunger 81 tends to create a partial vacuum within the cylinder 80. Therefore, during the cranking operation the cranking

gears are maintained fully in mesh so that the maximum tooth surface is available for transmitting the engine cranking force.

It will be noted that the piston element 81 cooperates with the cylinder element 80 only from the full meshed to the partly demeshed position of the pinion and that before the pinion is completely demeshed it may move free of the dashpot action. This construction is the result of providing for partly meshing the pinion free of dashpot action and works to advantage during the demeshing operation. There is sufficient dash pot operation to prevent axial movement of the pinion during the cranking operation but the dash-pot action is not sufficient to prevent demeshment of the engine gear when the engine starts under its own power. Although the dash-pot may retard the demeshing of the pinion during a certain part of its motion from full meshed toward demeshed position, the pinion is free of dash-pot operation from a partially demeshed position to a completely demeshed position so that the pinion may move with sufficient momentum from the gear in order to enable the pinion to clear the gear entirely.

In Fig. 6, showing a modified form of the invention, the gear housing 90 is provided with a cylindrical recess 91, providing a pressure cylinder for receiving a plunger 92 integral with a motor pinion 93, which is driven by the spiral splines 23. Telescopic engagement of parts 91 and 92 is facilitated by beveling the edges thereof at 91^a and 92^a, respectively, and endwise movement of part 92 is arrested by a stop collar 94 attached to armature shaft 24 and having a thrust bearing surface for engaging a companion thrust surface provided at the end of the cylindrical recess 91. The operation of this form of cushioning device is the same as that of the device shown in Figs. 1 and 2.

While the forms of embodiment of the invention as herein disclosed, constitute preferred forms, it is to be understood that other forms might be adopted, all coming within the scope of the claims which follow.

What is claimed is as follows:

1. Engine starting apparatus comprising a motor; means for connecting the motor with the engine including a pinion movable axially into mesh with a gear connected with the engine, and including provisions whereby, after the pinion has been partly meshed with the engine gear, operation of the motor will complete the meshing of the pinion with the gear; manually operable means for causing the pinion to be moved into mesh with the engine gear and for causing the motor to rotate the pinion, said means including an operating element and a spring for transmitting motion from said element to the

pinion; and cushioning means for retarding the movement of the pinion into full mesh with the engine gear, said cushioning means being constructed and arranged to be operative only after the pinion has been partly meshed with the engine gear.

2. Engine starting apparatus according to claim 1, in which the cushioning means is a fluid pressure device including coacting elements which are operatively engaged only after the pinion has been partly meshed with the engine gear.

3. Engine starting apparatus according to claim 1, in which the cushioning means comprises coacting piston and cylinder elements, one of which is movable with the pinion and engages the other only after the pinion has been partly meshed with the engine gear.

4. Engine starting apparatus according to claim 1, in which the cushioning means comprises a piston and a cylinder attached to the pinion and movable endwise with the pinion into engagement with the piston only after the pinion has been partly meshed with the engine gear.

5. Engine starting apparatus according to claim 1, in which a shaft supports the pinion for axial and rotary movement and in which the cushioning means comprises a cylinder provided by a recess in the hub of the pinion, and a piston carried by the shaft, the cylinder being movable into engagement with said piston.

6. Engine starting apparatus comprising a motor; a helically splined shaft driven by the motor; a pinion movable along said splines into mesh with the gear of an engine to be started and rotatable with the shaft for driving said gear; means for moving the pinion into mesh with the gear and for causing the motor to rotate the shaft; and means for retarding the movement of the pinion into complete mesh with the gear, said means comprising coacting piston and cylinder elements, one of which is movable with the pinion and the other of which is fixed upon the shaft.

7. Engine starting apparatus according to claim 6, in which the cylinder element is provided by a recess in the hub of the pinion and the piston is provided by a pinion stop member fixed to the shaft.

8. Engine starting apparatus comprising a motor; means for connecting the motor with the engine including a pinion movable axially into mesh with a gear connected with the engine, and including provisions whereby, after the pinion has been partly meshed with the engine gear, operation of the motor will complete the meshing of the pinion with the gear, said provisions tending to effect demeshment of the pinion when the engine gear tends to drive the pinion; a manually operable member causing the motor to drive the pinion; a pinion shifting member nor-

mally connected with the manually operable member; means for automatically disconnecting said members after the pinion has been at least partly meshed with the gear; 5 means for retarding movement of the pinion from part to full mesh with the gear, and tending to maintain the pinion in full mesh during the cranking operation, and constructed to permit demeshing of the pinion 10 when the engine becomes self-operative.

9. Engine starting apparatus comprising a motor; a helically splined shaft operated thereby; a pinion movable along said splines into mesh with the gear of an engine to be started and rotatable with the shaft to drive the gear; a manually operable member for causing the motor to drive the shaft; a pinion shifting member normally connected with the manually operable member; means 15

for automatically disconnecting said members after the pinion has been at least partly meshed with the gear; and fluid pressure means for resisting movement of the pinion into and part way out of mesh with the gear, said means comprising coacting cylinder and piston elements which are separated after the pinion has been partly demeshed but before the pinion has been fully demeshed 20 from the gear.

10. Engine starting apparatus according 30 to claim 9, in which the piston is provided by a pinion stop member fixed to the shaft, and the cylinder is movable with the pinion and engages the stop member only after the pinion is partly meshed with the gear. 35

In testimony whereof I hereto affix my signature.

GEORGE W. ELSEY.
